UNITED STATES PATENT OFFICE.

HERMAN RUFLL, OF INDIANAPOLIS, INDIANA.

CONTINUOUS-DISTILLATION STILL.

Application filed February 8, 1922. Serial No. 534,982.

To all whom it may concern:

Be it known that I, HERMAN RUFLL, a citizen of the United States, residing at Indianapolis, in the county of Marion and State 5 of Indiana, have invented certain new and useful Improvements in Continuous-Distillation Stills, of which the following is a specification.

This invention relates to distillation stills, and the prime feature of the invention is the provision of a plurality or battery of compartments through which the fluid to be distilled or treated is passed in succession, the degree of temperature gradually increasing as the fluid passes from one compartment to another.

A further feature of the invention is the provision of means for heating the contents of said compartments.

20 A further feature of the invention is the provision of means for conveying the liquid being treated from one compartment to the other under force.

A further feature of the invention is the provision of means for controlling the discharge of the distilling product into the various compartments.

A further feature of the invention is the provision of means for removing the residue from the last compartment of the battery,

35 And a further feature of the invention is the provision of means for excluding air from the discharge end of the compartment containing the residue.

Other objects and advantages will be hereinafter more fully set forth and pointed out in the accompanying specification.

In the accompanying drawings,

Figure 1 is a central longitudinal vertical section through the still showing the compartments in elevation,

Figure 2, a section on the line 2-2 of Figure 1,

Figure 3, a section on line 3-3 of Figure 1, and

Figure 4 is a perspective view of a closure plate for one of the compartments of the still.

Referring to the drawings, 1 indicates the still proper, which is preferably composed of a plurality of compartments 2, 3, 4 and 5, although it will be understood that any number of the compartments may be provided as occasion may require. The compartments 2, 3, 4 and 5, are preferably constructed of metal and are surrounded by

walls 6, each compartment being separated from the other by said walls, and the various walls are spaced from the compartments to provide heat passages 7, the lower ends 60 of the compartments being supported by or resting, however, on base walls 8. Immediately below the crown wall 9 passages 10 are formed through the separating walls 6, so that the heat passing upwardly around the 65 various compartments may escape from one compartment to the other and eventually enter a flue or chimney 11, located preferably at one end of the battery of compartments. At the opposite end of the battery of compartments from the flue 11 is a furnace 12 into which fuel is placed for heating the contents of the various compartments, the heat from the furnace passing from end to end of the battery of compartments through 70 passages 13 at the lower ends of the compartments and thence into the flue 11. This device is designed primarily for distilling petroleum, coal tar, and similar materials, and the material is first introduced into the 75 compartment 2 through a pipe 14 from any suitable source, said pipe being located adjacent the lower end of the compartment 2 and having a nozzle 15 thereon for controlling the discharge of the material. As 80 the material leaves the nozzle 15 it is thrown upwardly in the compartment 2, and spreads to the outer confines of the compartment so that the lighter or more volatile liquid elements of the material will be converted into 85 a vapor, and by providing an outlet 16 through the upper end of the compartment 2 the vaporized part of the material will pass out through said outlet 16 into any suitable condensing chamber, and to prevent any of 90 the liquid passing through the outlet 16, a shield 17 is arranged below said outlet around which the vapor passes when entering the outlet.

The body of the treated material descending to the lower portion of the compartment 2 is then discharged through a pipe 18 into the compartment 3, a nozzle 15 similar to the nozzle in the pipe 14 controlling the discharge of the liquid into the compartment 3. 100 The same process is repeated as occurs in compartment 2 and the volume of liquid descending into the lower end of the compartment 3 is conveyed into the compartment 4 through a pipe 19, and after treatment in the compartment 4 is conveyed to 105 the compartment 5 through a pipe 20, the

pipes 19 and 20 likewise having nozzles 15 thereon, and the compartments 4 and 5 are also provided with outlets 16 and shields 17.

As it is necessary to exert considerable force on the product being distilled, pumps 21 are provided for this purpose, these pumps being connected to the various pipes for conveying the material from one compartment to the next, and they may be of any preferred construction, although so operated that they will not create a vacuum in any one of the compartments while drawing the material being treated therefrom.

The device is preferably so constructed that the temperature within each succeeding compartment will be greater than that in the preceding compartment; that is to say: under normal conditions the temperature within the compartment 2 will be approximately 300 degrees Fahrenheit; that of the compartment 3, 500 degrees Fahrenheit; that of the compartment 4, 650 degrees Fahrenheit, and that of the compartment 5, 800 degrees Fahrenheit or over, with the result that the lighter or more volatile liquid products will be gradually removed when passing from compartment to compartment, thereby giving a finally treated material or residue in the compartment 5, and owing to the density of this liquid, the lower end of the compartment 5 is practically entirely open to allow the material to escape therefrom, the density of the material being such that it would not leave the compartment 5 through a small opening. Each nozzle 15 may be provided with a valve mechanism 22 for controlling the discharge of the liquid from the ends of the nozzles, said valve mechanisms preferably extending through the walls surrounding the compartments so that they may be readily manipulated. As there is normally more or less residue collecting in the lower ends of the compartments 2, 3 and 4, thereby gradually closing the openings in the ends of the pipes 18, 19 and 20, which connect respectively with the lower ends of the compartments 2, 3 and 4, overflow pipes 23 are provided which connect at their upper ends with the compartments 2, 3 and 4 at points above the lower ends of the compartments, while the lower ends of said overflow pipes connect with pipes 30, 31 and 32 at points exteriorly of the compartments, and if desired any suitable mechanism may be provided for determining the amount of residue collected within said compartments.

In addition to the provision of the furnace 12 for heating the various compartments, a fire box 24 may be located below the lower ends of each of the compartments 2, 3 and 4, so that additional heat may be applied under the respective compartments, if necessary.

Any suitable means may be provided for

removing the residue from the compartment 5, but in this instance a tank 25 is mounted upon a truck 26, and said truck is positioned below the discharge end of said compartment, and in order to prevent air gaining access to the interior of the compartment while one tank is being removed and another is being entered in position, a plate 27 is provided which is preferably three times the length of the tank 25, and which is provided with an opening 28 substantially the length of the tank through which the contents of the compartment 5 may enter the tank. The top edges of the tank fit snugly against the underside of the plate 27 and as soon as the tank has received its quota of the product it is moved from under the compartment 5 and below one of the imperforate ends of the plate, while a similar tank, previously positioned below the opposite imperforate end is simultaneously moved to position below the opening 28.

By providing a battery of compartments and gradually increasing the temperature of the successive compartments, the more volatile materials will be gradually vaporized and removed to a point of condensation as the material is carried from end to end of the battery of receptacles, so that by the time the material reaches and is treated within the compartment 5, all volatile particles will be removed and the residue remain.

Having thus fully described my said invention, what I claim as new and desire to secure by Letters Patent, is:

1. An apparatus for treating liquid comprising a plurality of compartments having means for transferring the liquid successively therethrough, the last compartment having an open lower end, an element beneath the bottom of said compartment having an opening to permit the discharge of residue therethrough, said element having oppositely extending portions projecting beyond the walls of the compartment and adapted to cover receptacles for receiving the residue whereby when one receptacle is under the opening receiving residue another receptacle will be under one of said projecting parts, substantially as set forth.

2. An apparatus for treating liquid comprising a plurality of compartments having means for transferring liquid successively therethrough, outlet passages at the upper ends of said compartments, shields spaced inwardly from the mouths of said outlet passages, heat passages around said compartments, communicating passages joining said heat passages adjacent the upper and lower ends of said compartments, said last compartment having an open lower end, an element beneath the lower end of said compartment having an opening therein for the

removal of residue, said element having oppositely extending portions projecting beyond the wall of the compartment and adapted to cover receptacles for receiving

the residue whereby when one receptacle is under the opening receiving residue another receptacle will be under one of said projecting parts, substantially as set forth.

In witness whereof, I have hereunto set my hand and seal at Indianapolis, Indiana, 10 this 4th day of February, A. D. nineteen hundred and twenty-two.

HERMAN RUFLI. [L.S.]
